UNITED STATES PATENT OFFICE.

CARL LUCKE, OF EILENBURG, NEAR LEIPZIG, GERMANY.

STEAM-GENERATOR.

No. 844,158.

Specification of Letters Patent.

Patented Feb. 12, 1907.

Application filed December 18, 1906. Serial No. 348,435.

To all whom it may concern:

Be it known that I, CARL LUCKE, subject of the Emperor of Austria, residing at Eilenburg, near Leipzig, Germany, have invented 5 new and useful Improvements in Steam-Generator Without Water-Space, of which the following is a specification.

This invention relates to a steam-generator without water-space with outlet for the 10 water in the evaporator and provided with a device for bailing the water out of the outlet-pipe.

This invention is set forth in the following 15 specification and claims and illustrated in the annexed drawings, in which—

Figure 1 is a longitudinal section of a steam-generator in connection with a bailing device in form of a plug. Fig. 2 shows the construction of Fig. 1 in cross-section. Fig. 20 3 is a longitudinal section through a bailing or emptying device with double piston. Fig. 4 is a section of a modification with two cocks.

The drawings show a steam-generator in form of a cylindrical reservoir A, which is in 25 communication with feed-pipe B at one side or end and with outlet-pipe C at the other. The feed-pipe extends along in the evaporator through its length, and such pipe is provided with a row of discharge openings or 30 jets for the water. In the construction shown in Figs. 1 and 2 of the bailing or emptying device the outlet-pipe D, leading from the bottom of the evaporator, is in communication with the housing E of a rotary plug F, 35 which by means of a rod G is kept in continuous rotary motion by any source of power. This plug is provided with a bailing-space H which, through the rotary or actuating motion of rod G alternately communicates with 40 the outlet-pipe D and with the outlet-pipe I. So long as the bottom of the evaporator is free from water the bailing-space H of the plug F is filled with steam, which in turn passes out through pipe I. Likewise ac- 45 cumulated water is also at once carried off

through the bailing-space H to the pipe I. The plug F is so small that its bailing-space suffices to carry off the accumulating water or water mass. The quantity of the wasted steam carried off, however, is so small that 50 the efficiency of the steam-generator is but slightly affected.

In the modification of the bailing device as shown in Fig. 3 two pistons K and L are secured to the rod M, and as the pistons are 55 actuated the mouth of the outlet-pipe D is alternately closed or opened. By the opening of the mouth of the outlet the water is allowed to enter between the two pistons, and such water is then on the return stroke 60 carried to the outlet-pipe I.

In the modification Fig. 4 are shown two cocks K and L, which are actuated by actuating-rod M. The water coming from pipe D passes through cocks K to the space between the cocks, and as the cocks are turned forty-five degrees (45°) the cock K closes and cock L opens, and the water passes off through inlet I.

I claim—

1. A steam-generator comprising an evaporating-chamber combined with a discharge-tube for the water deposited in such evaporating-chamber, and a continuously-actuated discharge-valve made to alternately 75 communicate with the discharge-tube and with the open air.

2. A steam-generator comprising an evaporating-chamber combined with a discharge-tube for the water deposited in such evaporating-chamber, and a continuously-actuated two-piston valve made to communicate with the discharge-tube.

In testimony whereof I have hereunto set my hand in the presence of two subscribing 85 witnesses.

CARL LUCKE.
